EXHIBITING DEVICE

William A. McCombs, New York, N. Y.

Application January 12, 1935, Serial No. 1,479
Renewed September 8, 1938

21 Claims. (Cl. 40—32)

This invention relates to exhibiting devices, particularly to those which include a movable endless strip or web upon which appear advertisements or other matter to be exhibited.

5 One object of our invention is to provide a device of this character which is adapted to utilize a relatively long endless strip in a comparatively small space. A further object is to provide a device of this character with a specially constructed hopper for containing or storing loose or excess portions of the moving strip and a further object is to provide an arrangement of parts such that the strip is fed into the hopper by gravity.

10 15 A further object is to provide a novel arrangement of rolls for guiding and for moving the strip and also means for preventing entanglement of the loose portions of the strip by the guiding and actuating rolls.

20 25 A further object is to provide an improved exhibiting device having a window or opening behind which the movable strip is passed for exhibition, vertically upward or in a direction toward the top of the sign, printed or other matter appearing on the strip.

30 35 A further and important object of our invention is to provide an improved means for accurately aligning the strip as it is fed out of the hopper onto suitable guiding rolls, in its passage toward the display window. In the specific embodiment of our invention herein disclosed, this object is attained by inclining the side walls of the hopper toward the point from which the strip is removed, so that the side walls form a guiding means for the strip to insure accurate positioning of the strip on the guide rolls.

40 Other objects of our invention include simplicity of construction, relatively small cost of manufacture and durability and also to provide a device of this character which is entirely automatic in operation and requires no attention for long periods of time.

45 Other objects and advantages of our invention will appear from the following description taken in connection with the accompanying drawings which show one embodiment of the invention and wherein:

50 Figure 1 is a vertical sectional view looking into the exhibitor casing from the front, the section being taken on the line 1—1 of Figure 2 with certain of the parts being broken away;

55 Figure 2 is a vertical section taken on the line 2—2 of Figure 1;

Figure 3 is a perspective view of the exhibitor casing;

Figure 4 is a detail sectional view taken on the line 4—4 of Figure 1;

Figure 5 is a detail sectional view taken on the line 5—5 of Figure 4 and showing the means for pressing a friction roll into contact with the driving roll for the strip;

Figure 6 is a top plan view, partly broken away, of the mechanism holding frame adapted for insertion into the display cabinet;

Figure 7 is a side elevation of the structure shown in Figure 6;

Figure 8 is a schematic view showing a modification of the holding means for the tapes which forms the hopper; and

Figure 9 is a fragmentary view similar to the bottom of Figure 2 but showing a modification.

The mechanism of the exhibiting device is contained in a casing or cabinet 10 shown, for example, in Figures 2 and 3, which casing may be made of wood or other suitable material and is formed with an opening 11 at its front closed by a pane of glass 12. Reference character 14 represents the strip or sheet having the advertising matter thereon and which is adapted to be moved upwardly immediately behind the window 11.

Adapted to carry the strip 14 as well as the mechanism for moving and guiding the same is a frame 19 which is removably mounted in the cabinet and comprises a base 13, front and back inverted U-shaped frame members 17 and 15 respectively suitably secured by bolts 18 to the base 13. Members 17 and 15 are connected by inclined side walls 16 and it will be seen that the uprights of the U-shaped member 17 are spaced farther apart than are the uprights of member 15 and the walls 16 are inclined toward each other rearwardly for a purpose which will be more fully explained hereafter.

Means for moving the strip comprises an electric motor 20 mounted on top of the frame member 17. The shaft of the motor 20 carries a pulley or sprocket wheel 22 over which passes a belt or chain 23 engaging a small pulley or sprocket wheel 24 mounted on one end of a stub shaft 25 journaled in a bearing 26 supported from the inner side of one of the uprights of frame member 17. Secured to the opposite end of the shaft 25 is a roll 30 for moving the strip 14; this roll at its far end carrying a stub shaft 25 journaled in a bearing 26 supported from the inner side of the opposite upright of the member 17. The roller 30 has a rubber facing 31 which is interrupted at intervals, as shown in Figures 4 and 6 to form annular recesses 32 for

a purpose hereafter to be explained. Mounted adjacent and parallel to the roll 30 is a roll 34 having rings or collars 35 of rubber or similar material. The roll 34 is an idler roll mounted 5 at opposite ends on arms 37 pivoted at 38 on the opposite uprights of frame member 17 and normally urged toward the roll 30 and into contact with the strip 14 by means of springs 39 secured at one end to the upright and at the 10 opposite end of the lower end of arm 37.

Rotatably mounted in bracket bearings 40 immediately below the brackets or bearings 26 and 26' is a roll 41 over which the strip 14 passes and below this roll 41 at the bottom of the upright 15 portions of the member 17 is a roll 42 beneath which the strip passes in its travel to a position immediately behind the window 11. To the rear of roll 42 is a roll 44 beneath which the strip 14 passes on its way to the upper roll 41.

20 Mounted at the rear of the frame 19 near the top of the inverted U-shaped member 15 is a roll 51 over which the strip passes as it is fed out of the hopper and mounted near the lower end of the member 15 of the frame 12 is a roll 52 beneath 25 which the strip passes in its passage from rear roll 51 to the forward roll 44.

The space between the rear rolls 51 and 52 and the front rolls as will be seen forms a container 30 adapted to hold a relatively large quantity of loose strip which is fed downward thereinto from the feeding roll 30. The passage of the strip from the hopper is as follows: Leaving the hopper it passes upward over the roll 51, thence downward under the roll 52, thence under roll 44 upward 35 over the top of roll 41, thence downward under the roll 42, thence upward past window 11 and over the roll 30 and between the roll 30 and the idler roll 34 downward into the hopper. By tapering the hopper rearwardly to a narrower 40 width equal approximately to the width of the strip 14, the hopper provides ample space into which the strip passing over roll 30 may fall freely into natural folds and at the same time be guided by the sides of the hopper into proper position on the roll 51. It will thus be seen that the 45 apparatus is adapted to utilize a strip of considerably greater length than the distance around all of the rolls.

In order to prevent loose folds of strip contained 50 in the hopper from being enmeshed or entangled by the moving rolls 52 and 44 and the moving strip which is passing under these rolls, I form these rolls and the roll 51 with cutout 55 portions 60 which, if desired, may be formed by interruptions in the rubber facings of the rolls, these interruptions or annular recesses being arranged along the length of the rolls and in line with the recesses 32 in roll 30. I secure to the rolls 51 and 30 pieces of tape, wire or similar 60 strips 63 which at their ends are looped around these rolls 54 and 30 in the recesses and sewed or otherwise secured such as at 65. These pieces of tape extend beneath the rolls 52 and 41 in their respective recesses. I have shown in Figure 1, 65 three pieces of tape. Also at the rolls 52 and 44, I provide additional pieces 66 which pass over the rolls and are sewed above and below to the main section of tape. It will be thus seen that these tapes in effect form a hopper for loose or 70 excess strip and also prevents the loose portions of strip being drawn in by the rolls or by the guided portion of the moving strip.

When the length of the strip is but slightly in excess of the distance around the rolls, the 75 strip will form a single fold or bend in the hopper

and if desired, under these conditions, I may support a floating roll 70 by, and in, the fold as shown for example in Figure 9.

In the modification shown in Figure 8, instead of passing the tapes under the lower rolls, I provide two rods 68 mounted respectively in the members 15 and 17 under which rods the tape passes. 5

It will be noted that the hopper extends substantially the full length and width of the cabinet 10 net and therefore has a relatively large capacity.

Suitable means not shown may be provided for controlling the motor either to cause it to operate continuously or intermittently. It will be seen that by causing the strip to move behind 15 the window vertically it is possible to use a relatively wide strip with a large amount of printed matter thereon, the movement of the strip presenting this matter to view in the order in which it is read. Bearings 26 and 26' at opposite ends 20 of roll 30 as well as the bearings at opposite ends of each of the other rolls are preferably of the self-aligning and self-lubricating type.

If desired, suitable means may be provided for illuminating the strip. 25

Having now described my invention what I claim and desire to secure by Letters Patent is:

1. In an exhibiting device, an endless display strip, means for moving the strip, a hopper for containing excess portions of the strip, means 30 for feeding the strip into the hopper, and withdrawing it therefrom at points adjacent the upper end of the hopper, the length of the strip employed with respect to the capacity of the hopper being such that folds of the strip in 35 the hopper are maintained, by gravity, remote from the point of delivery, guides for directing the strip around the hopper and guides for positioning said strip accurately along said first named guides. 40

2. In an exhibiting device, a cabinet having a display window in front, an endless display strip, guides for the strip at substantially the top of the cabinet at the front and back and guides for the strip at substantially the bottom 45 of the cabinet at the front and back, said guides forming between them a hopper for containing loose portions of the moving strip, means for feeding said strip into said hopper from the top and withdrawing it from the top of the 50 hopper and for guiding said strip around three sides of said hopper.

3. In an exhibiting device, a cabinet having a display window in front, an endless display strip, guiding rolls for the strip at substantially 55 the top of the cabinet at the front and back and guide rolls for the strip at substantially the bottom of the cabinet at the front and back, said rolls forming between them a hopper for containing loose portions of the moving strip, means for feeding said strip into the hopper from the top front guide roll and withdrawing it from the top rear guide roll and moving the guided strip around three sides of the hopper and means for preventing engagement of loose portions of the 60 strip by the guide rolls. 65

4. In an exhibiting device, an endless display strip, means for moving said strip, upper and lower spaced guide rolls forming between them 70 a space for containing loose portions of the moving strip and means for preventing engagement of loose portions of the strip by the rolls, said means consisting of spaced pieces of tape supported along the sides of said space. 75

5. In an exhibiting device, an endless display strip, spaced upper and spaced lower rolls, said rolls forming between them a space for containing loose portions of said strip, means for feeding said strip into said space over one of the top rolls and withdrawing the strip over the other top roll, and means for preventing engagement of loose portions of the strip by the lower rolls, said means consisting of pieces of tape secured around the top rolls and passing under the bottom rolls and shorter pieces of tape extending over the bottom rolls and secured at opposite ends to said first named pieces. 5

6. In an exhibiting device, an endless display strip, spaced upper and spaced lower guide rolls formed along their length with annular recesses, said rolls forming between them a space for containing loose portions of said strip, means for feeding said strip by gravity into said space over one of the top rolls and withdrawing the strip from said space over the other top roll and means for preventing engagement of the loose portions of the strip by the lower rolls and by the guided portions of the strip, said means consisting of pieces of tape secured around the top rolls and passing under the bottom rolls and lying in said recesses and shorter pieces of tape extending over the bottom rolls and secured at opposite ends to first named pieces. 10

7. In an exhibiting device, an endless display strip, means for moving the strip, a casing having a window, means for guiding the strip past the window, a hopper for containing excess portions of said strip, means for feeding the strip into the hopper at one point and withdrawing it at another point, said hopper at said one point having a width substantially greater than the width of the strip and gradually narrowing toward the other point to a width substantially that of the strip. 15

8. In an exhibiting device, an endless display strip, means for moving the strip, a casing having a window, means for guiding the strip past the window, a hopper for containing excess portions of said strip, means for feeding the strip into the hopper at the front and top of the hopper and withdrawing the strip at the back and top of the hopper, means for maintaining folds of the strip in the hopper remote from the point of withdrawal, said hopper tapering rearwardly from a width substantially greater than that of the strip to a width substantially that of the strip. 20

9. In an exhibiting device, an endless display strip, means for moving said strip, upper and lower spaced guide rolls forming between them a space for containing loose portions of the moving strip and means for preventing engagement of loose portions of the strip by the rolls, said means consisting of spaced strips supported along the sides of said space. 25

10. In an exhibiting device, an endless display strip, a hopper, means for moving the strip into the hopper and withdrawing it therefrom at one side thereof and means for guiding the strip around three sides of the hopper and exhibiting the same while so guided. 30

11. In an exhibiting device, an endless display strip, a hopper, means for moving the strip into the hopper and withdrawing it therefrom at the top of the hopper, means for guiding the strip around two sides and the bottom of the hopper and exhibiting it while so guided. 35

12. In an exhibiting device, an endless display strip, means for moving said strip, upper and lower spaced guides forming between them a space for containing loose portions of the strip and means for preventing engagement of loose portions of the strip by the guides, said means consisting of tape supported inside the guides. 40

13. In an exhibiting device, an endless display strip, means for moving said strip, upper and lower spaced guide rolls forming between them a space for containing loose portions of the moving strip and means for preventing engagement of loose portions of the strip by the rolls, said means consisting of tape supported along the sides of said space. 45

14. In an exhibiting device, an endless display strip, means for moving the strip, a casing having a window, means for guiding the strip past the window, a container for excess portions of the strip, means for feeding the strip into the container and withdrawing it from the top of the container, said strip extending as a bend down into the container and a floating roll in the container supported by and riding upon the bend. 50

15. In an exhibiting device, an endless display strip, means for moving the strip, a casing having a window, means for guiding the strip past the window, a container for portions of the strip, means for feeding the strip into the container and withdrawing it from the top of the container, said strip extending as a bend down into the container and a floating weight in the container supported by and riding upon the bend. 55

16. In an exhibiting device, an endless display strip, a hopper, means for moving the strip into the hopper at one side thereof and withdrawing it therefrom at the same side and means for guiding the strip around the sides of the hopper and exhibiting the same while so guided. 60

17. In an exhibiting device, a casing, a continuous strip, means for guiding said strip along a plurality of sides of said casing and said strip while so guided forming a container for receiving loose portions of said strip, and a roll in said container for insuring the positioning of said loose portions over substantially the height of said container. 65

18. In an exhibiting device, a casing, a continuous strip, means for guiding said strip along a plurality of sides of said casing and said strip while so guided forming a container for receiving loose portions of said strip, and a roll in said container for insuring the positioning of said loose portions over substantially one dimension of said container. 70

19. In an exhibiting device, an endless display strip, means for moving the strip, a casing having a window, means for guiding the strip past the window, a container for loose folded portions of the strip, means for feeding the strip into the container substantially at the top or at a point above said loose folded portions and withdrawing the strip from the container substantially at the top, or at a point above, said loose folded portions. 75

20. In an exhibiting device, an endless display sheet, means for moving the sheet, a hopper for containing loose ends of the sheet, means for feeding the sheet into the hopper and withdrawing it therefrom, rollers for guiding said sheet around sides of the hopper, said rollers having spaced peripheral channels and said hopper comprising stationary strips extending along the sides thereof and projecting into said channels whereby dragging of the sheet between the strips and rollers is avoided. 80

21. In an exhibiting device, an endless display strip, means for moving the strip, a casing having a window, means for guiding the strip upwardly past the window, a container for excess portions of said strip, means for feeding the strip into the container substantially at the

top or at a point above said excess portions, and withdrawing the strip from the container substantially at the top or at a point above said excess portions.

WILLIAM A. McCOMBS. 5
